LUBRICATING MEANS

Application filed September 26, 1929. Serial No. 395,394.

This invention relates to improvements in oiling devices and particularly such devices as are applicable to explosive engines.

The principal object of the invention is to provide a device of this character, by means of which oil may be first finely divided into spray, and then sucked into the explosion chambers of the engine.

The devices heretofore known in the art, so far as we are aware, are defective in that the suction created by the pistons of the engine is not always sufficient to cause the oil to be sucked up in the form of spray from the oil container with any uniformity of operation. That is to say, due to the relatively large cross sectional area of the oil containers heretofore known in this art, the suction of the pistons was sufficient to fairly well cause the flow of lubricant so long as the container was full or approximately full of oil, but due to the relatively large cross sectional area of the oil container itself, with respect to its depth, the suction would bring up a constantly decreasing volume of oil as the level of the oil descended, until finally a point would be reached when the oil level in the container was so low that the device would cease to function.

We correct this defect by so arranging the parts that the suction force is directed to a tube or chamber of relatively small cross sectional dimensions with the result that the engine will be lubricated so long as there is any oil in the container at all.

A further object is to provide a tank having a tube of the same height which has an oil inlet at the lowermost portion thereof, an air inlet opposed to said oil inlet so that the air and oil may be drawn into the tube together, and a means for exhausting the air in the tube above the oil level to thereby completely fill the tube with aerated oil.

A still further object is to inject the mixture of oil and air into the center of the intake manifold so that the oil will be thoroughly mixed with the gas and air in the manifold.

The invention is illustrated in the accompanying drawings, in which:

Figure 1 is a vertical sectional view of the device.

Figure 2 is a top plan view.

Figure 3 is a vertical sectional view taken upon the line 3—3 of Figure 2.

Figure 4 is a bottom plan view, partly in section, of the usual vertical pipe with its branches which run to the explosion chambers, or, in other words, of the usual intake manifold.

Referring now more particularly to the drawings, reference numeral 1 indicates the oil container, which is adapted to be screwed to a convenient part of the body of the vehicle by means of strips 2, said container having an intake port 3 for the oil, which is normally closed by a screw cap 4, there being a pipe 5 extending downwardly a short distance from the intake port, its mouth being preferably covered by wire or other such screening 6.

An outlet port 7 from the container includes a nut 8, through which passes a pipe 9, bent as shown in Figure 1. The outer end of the pipe is equipped with a needle valve construction including a threaded stem 10, having a head 11 upon one end, the other end terminating in the needle proper 12, which normally rests within a seat 13.

A branch 14 from the pipe 9 receives one end of a pipe 15, preferably of the usual copper formation, readily bendable. The other end of the pipe is adapted to pass through the main vertical stem 16 of the usual manifold having branches 17, as usual. This terminal of the pipe is not flush with the interior wall of the pipe 16, but passes through it so that its free terminal is about central with the center of the pipe 16, and is preferably flared.

A tube 19 having its bottom end open is fixed within a base portion 20. A passage 21 from the container 1 connects said container to the tube 19, the top being preferably of glass or other transparent material. A nut 21^A is threaded into a projecting portion 20^A of the container and bears against a shoulder 22^A of a pipe 22, forcing said pipe onto a resilient gasket 23 between the tube and the nut, so that when the nut is screwed downwardly, the gasket will relieve the tube from any un-

due bending that might tend to crack or break the tube and also provide a sealed connection between the tube and pipe.

5 The pipe 22 is threaded into the valve at 24, so that the pipe 19 communicates with the pipe 9. Another tube 25, whose lower end is secured within the base 20, is connected to the tube 19 by means of a passage 26, its upper end passing through the projected portion 10 20^a. A nut 27 having air vents 28 through which air is admitted into the pipe 25, thence through the passage 26 into the tube 19, is threaded into the portion 20^a and is in direct connection with the tube 25.

15 The operation of the device is as follows:— The container being filled with oil, the engine not running, the oil will be of the same level in the container, tube 19 and tube 25. When the engine is started, the pressure is 20 decreased above tube 19 and container 1. This causes the relatively increased or atmospheric pressure above tube 25 to force the oil in said tube 25 into tube 19 and container 1. Tube 25 terminating below the lower level of tube 25 19 and tube 19 being above container 1, the air forced in through tube 25 would entirely escape through tube 19 bubbling upward through the oil in that tube and carrying with it through tube 15 a certain minute amount 30 of oil. Due to the tank 1 being lower than tube 19, the air will entirely escape through tube 19, while the even decrease of pressure over tube 19 and tank 1 would hold the oil at the same level in both. The oil-laden air 35 is carried through tube 15 and discharged through the nozzle in the manifold. The result of this is that a finely divided spray formation of oil is continually applied to the interior of the combustion chamber and the working parts therein. If the end of the pipe 40 15, which connects with the intake manifold 16, were flush with the interior walls of the intake pipe, then of course the oil would flow in the course just described, but a portion of 45 it would trickle down the interior walls of the pipe 16 and not be subjected to the upward suction within the pipe 16 with any uniformity.

To correct this we provide a hollow T casting 50 27^a, counterbored and internally threaded, as at 27^b, so that the usual pipe 27^c, leading to the usual vacuum system, may be threaded into the counterbored portion 27^b. The casting is externally threaded at 27^d, so 55 as to be passed through an aperture in the intake manifold 16, and secured in that position by the said threads, the T casting projecting some distance into the manifold 16, as clearly shown in Figure 4, there being a pipe 27^e thrust into the hollow casting and having one of its ends projecting to the left 60 some distance and having a plurality of apertures 27^f, the left hand end of the tube being substantially in the vertical center of the intake manifold 16, so that the finely divided

oil which escapes through the apertures 27^f may permeate the entire interior of the manifold 16 and be subjected to the upward draught created by the action of the pistons.

It is apparent that we do not attempt to cause the oil spray to be taken directly from the surface of the oil in the container 1, but, on the contrary, lift the oil from the relatively small area within the pipe 19 so that the oil from the container 1 is discharged from the bottom of the container 1 into the pipe 15 and thence into the manifold instead of being discharged from the top, thus insuring a steady flow of the oil at all times instead of a flow which would decrease as the level of the oil descended. The net result is that the oil passes in uniform bubbles and in uniform flow so long as there is any oil in the container at all.

80 What is claimed to be new is:

An oil injecting device comprising an oil container, a base portion formed with a conical-shaped depression, a tube seated in said depression, a second tube carried by said base portion, a passage from said container, a second passage from said second tube, both of said passages terminating in said conical-shaped depression, whereby the air entering the first tube by the second mentioned passage will not pass through the first mentioned passage but be directed upward through said first mentioned tube.

85 In testimony whereof we affix our signatures.
